UNITED STATES PATENT OFFICE.

LOUIS NAGLEE BRUNER, OF ZURICH, SWITZERLAND.

MACHINE FOR GRINDING GLASS BOTTLES AND OTHER ARTICLES.

1,301,376.

Specification of Letters Patent. Patented Apr. 22, 1919.

Application filed November 8, 1916. Serial No. 130,283.

To all whom it may concern:

Be it known that I, LOUIS NAGLEE BRUNER, a citizen of the United States of America, residing at 7 Bellerivestrasse, Zurich, Switzerland, glass manufacturer, have invented certain new and useful Improvements in Machines for Grinding Glass Bottles and other Articles, of which the following is a specification.

10 This invention has reference to machines for grinding glass bottles and other articles, and is designed more particularly to provide a machine for automatically grinding the outer surfaces of bottle mouths, so that 15 the mouths of any number of bottles can be made all exactly alike.

The invention is very advantageous in connection with the known system in which the same stopper or cap will fit any one of 20 the bottles thus securing the advantage of interchangeability and obviating the necessity for separately grinding each bottle for its own stopper or cap in the ordinary way.

25 A feature of the invention consists in arranging the bottle so that it is automatically inserted in a chuck arrangement by a rotary feed drum, and a grinding disk or wheel is then caused to act on the portion to be 30 ground while the bottle is rotated around its axis, this disk while operating moving to and fro sidewise. The operative edge of the disk is acted on by a diamond device to keep it always exactly true, and an automatic adjusting device having a micrometer action, 35 is provided to feed the disk forward by the necessary amounts to make up for wear.

Another feature of the invention is that all the operations are performed automatically 40 under the control of cams, by the machine itself, so that all the operator has to do is to place the supply of unground bottles in the feed chute or hopper hereinafter mentioned.

45 After the grinding, the bottle is released by the chucks and the feed drum rotates sufficiently to bring the next bottle into position, the ground bottle being dropped out into a receiver. At the same time a fresh bottle 50 drops from the aforesaid feed chute or hopper into a cell or cavity in the drum, ready to be carried at the next movement of the latter, into the grinding position.

In order that the invention may be clearly 55 understood and readily carried into effect

reference will now be had to the accompanying diagrammatic drawings in which:—

Figure 1 is a side view, and

Fig. 2 is a plan of one example of the improved machine.

Fig. 3 is a detail end view of the feed drum.

In this example of apparatus according to the invention, A is the feed drum which is provided with three receiving cavities, cells 65 or recesses A* disposed around it at equal distances apart, and so arranged that as they successively pass the position 1 (Fig. 3) they can each be supplied with a bottle a automatically or otherwise.

As the drum A rotates, the bottle a is brought into the grinding position wherein it lies in line with a centering pin or cone b over which its mouth will fit, and with a chuck or holder c which has previously been 75 drawn back out of the way, but which is adapted to grip its rear end. This rear chuck is now moved up toward the bottom of the bottle to clamp the latter in place, a cushioning spring c* being combined with 80 the chuck to allow for slight inequalities in the length of the bottles. The bottle lies loosely in the recess A* and the action of the cone b and chuck c is such as to lift it up slightly so that under the action of the belt 85 pulley h, it can revolve in the said recess quite freely but clear of the walls thereof.

The movement of the chuck is effected by a lever d and a second lever d¹, a connecting rod e and a lever f worked by a cam g¹ on 90 the main shaft g. This shaft is supported in bearings g*.

Constant rotary motion is imparted to the aforesaid centering cone b and chuck c by the pulley h. This pulley drives the chuck 95 c directly, and it also drives the cone b at exactly the same speed by a suitable train of gears i, i¹, i², i³. Of these i¹ and i² are mounted on a shaft i* which is thus constantly rotated.

100 The grinding wheel k is mounted on an adjustable slide or carriage k¹ and is driven by a belt-pulley k³. It is caused to work to-and-fro sidewise on a saddle k* during the grinding by an adjusting link k², a cam n 105 and a suitable set of levers o. The link k² is adjustably connected to a swiveling block k⁴ carried by a bearing k⁵ at the end of one of the arms or levers o.

Hence when the bottle is held in or 110

gripped by the chuck, it immediately rotates therewith, and the grinding wheel k is then moved toward it for instance by a suitable cam g^2 so as to grind the outer or tapered 5 surface a^1 of the bottle mouth. The said cam g^2 acts for instance through a forked lever, the prongs m of which (see in plan in Fig. 2) engage in a grooved collar m^x on a feed-screw m^1 . The adjustment to make up 10 for wear of the tool itself, which is extremely slight, may be effected by turning the feed-screw m^1 by a hand-wheel m^2 or by a micrometer feed such as described in the specification of my concurrent application Serial 15 No. 131163.

When the grinding is finished, the cam g^1 moves the chuck back again, so releasing the bottle. Then a clutch p , which transmits motion to the feed drum A, is put into 20 engagement until it has caused the feed drum to make one-third of a revolution.

The step-like movement is given to the drum A by a pinion r^2 , being transmitted through the clutch p , of which the fast or 25 right-hand revolving part is driven by gears r^1 r^3 . Of these, the gear r is fast on the shaft i^x .

The pinion r^2 is, at the proper times, thrown into action by a cam q and lever q^1 30 which control the clutch p . The pinion r^2 has a nib r^4 which rides on to the end surface of the bearing r^5 and once there keeps the clutch p in engagement until the pinion r^2 comes around, when the nib re-enters its 35 recess or seating, and so allows the clutch to open. The revolution of the pinion causes the gear wheel r^3 and the carrier drum or cylinder A to give one-third of a turn, to bring a fresh bottle into position for grinding.

The carborundum wheel k (Fig. 2) is then actuated, and trues up the outer surface a^1 of the bottle mouth, accuracy being insured by the action of a gage diamond s in 45 the known manner.

Alongside the cam g^1 is another cam g^2 which as stated moves the grinding wheel saddle k^x toward and from the bottle mouth. These two cams, and also cam q at the left- 50 hand end of the same shaft g , are driven from a pulley v at the right-hand end through a train of gears $t-t^3$.

The cam n near the pulley v which serves for traversing the grinding wheel backward 55 and forward along the mouth a^1 is fast to the wheel t^1 but is loose on the shaft g and rotates much more rapidly than the said shaft. The shaft g for instance may make one revolution per minute while cam n 60 may make about ten, which of course gives

ten reciprocations to the grinding wheel, and thus one bottle can be taken in, ground and discharged at each revolution of the cam shaft g .

The bottle-carrier A (see Fig. 3) takes the 65 bottles in at the side position 1, brings them into the grinding position (2), and drops them out at the position 3.

After the bottle in the left-hand cavity, Fig. 3, is ground it comes into the bottom 70 position and drops out, and the next bottle (in the right hand cavity) comes into the grinding position, after which the above operations are repeated, a fresh bottle entering the cavity which was previously at 75 the bottom but has now moved to the right-hand position.

The feed drum is mounted on two fixed sleeves A^1 A^2 one at each end thereof, and is directly connected with the gear wheel 80 r^3 which drives it, by a neck or hub portion A^3 .

Obviously the invention may be modified in various ways in carrying the same into practice without departing from the general 85 nature thereof.

I claim:

1. In a machine for grinding glass bottles, the combination of a chuck arrangement for holding the bottle at both ends, a rotary feed 90 drum, a grinding disk and cams for automatically controlling the action of said chuck, drum and disk, substantially as described.

2. In a grinding machine the combination 95 of a chuck for holding the article at each end, a grinding apparatus, cams for controlling said chuck and for moving the grinding apparatus up to and away from the work at the proper times, and a feed drum with recesses to receive the articles to be ground the chuck being so arranged that it raises the article slightly when gripping it and thus permits it to rotate while still in the recess of the drum.

3. In a machine for grinding glass bottles the combination of a feed drum having recesses to receive the bottles, a chuck arrangement which lifts the bottle slightly when gripping it, a reciprocating grinding mechanism, and cams all mounted on one and the same shaft for controlling the action of said parts, substantially as described.

In testimony whereof I have signed my name to this specification.

LOUIS NAGLEE BRUNER.
